(57) **CLAIM**

The ornamental design for a fan duster with swivel head, as shown and described.

DESCRIPTION

FIG. 1 is a perspective view of an embodiment of the fan duster with swivel head of the claimed design;

FIG. 2 is a front elevational view of the fan duster with swivel head of FIG. 1;

FIG. 3 is a rear elevational view of the fan duster with swivel head of FIG. 1;

FIG. 4 is a right side elevational view of the fan duster with swivel head of FIG. 1;

FIG. 5 is a left side elevational view of the fan duster with swivel head of FIG. 1;

FIG. 6 is a top plan view of the fan duster with swivel head of FIG. 1;

FIG. 7 is a bottom plan view of the fan duster with swivel head of FIG. 1;

FIG. 8 is a perspective view of another embodiment of the fan duster with swivel head of the claimed design;

FIG. 9 is a front elevational view of the fan duster with swivel head of FIG. 8;

FIG. 10 is a rear elevational view of the fan duster with swivel head of FIG. 8;

FIG. 11 is a right side elevational view of the fan duster with swivel head of FIG. 8;

FIG. 12 is a left side elevational view of the fan duster with swivel head of FIG. 8;

FIG. 13 is a top plan view of the fan duster with swivel head of FIG. 8; and,

FIG. 14 is a bottom plan view of the fan duster with swivel head of FIG. 8.

The features shown in broken lines are environment only and not part of the claimed design.
